MECHANISM FOR CUTTING POTATO CHIPS
OR THE LIKE

Donald A. Barnes, Akron, Ohio

Application April 13, 1939, Serial No. 267,658

2 Claims. (Cl. 146—125)

The invention relates to cutting mechanisms and it has particular relation to a mechanism for cutting potato chips or the like.

Potato chips are known to everyone and it is hardly necessary to state that they comprise thin slices of potatoes, which, after cooking, are crispy in character. The present invention is concerned principally with the slicing of a potato which is to provide a chip corrugated in form.

One object of the invention is to provide a simple mechanism for cutting slices or chips from potatoes, wherein each chip or slice has corrugations on its opposite sides, with the corrugations on one side traversing the corrugations on the other side.

Another object of the invention is to provide a mechanism of this general character which cuts the slices or chips in a uniform manner, so that the finished product will be of uniform character and thickness.

Other objects of the invention will become apparent from the following specification, from the drawing relating thereto, and from the claims hereinafter set forth.

For a better understanding of the invention, reference may be had to the drawing, wherein:

Figure 1 is an elevational view, partly in cross-section, illustrating a mechanism constructed according to one form of the invention;

Fig. 2 is a cross-sectional view, taken substantially along the line 2—2 of Fig. 1;

Fig. 3 is a detail view illustrating a rotary cutter disc employed in the mechanism, with the cutter blade attached thereto;

Fig. 4 is a cross-sectional view on a larger scale taken substantially along the line 4—4 of Fig. 3; and

Fig. 5 illustrates on a larger scale a potato chip sliced from a potato by the mechanism.

Referring to Fig. 1, the mechanism comprises a base 10 having a vertically arranged motor 11 therein which is supported on a plate 12 secured to the lower side of the base by screws 13. At its upper end, the motor 11 is anchored to the sides of the base by brackets 14. The upper end of the motor shaft is tapered, as indicated at 15, and this tapered end projects into a socket element 16 and is keyed thereto as indicated at 17. This socket element has a smaller threaded stub portion 18 that projects through a central opening in a metal disc 20 and for holding the disc on the stub portion, a nut 21 is threaded on the stub portion into contact with the upper side of the disc. A drive pin 23 drivingly connects the disc and socket member.

At its upper end, the stub portion 18 projects upwardly through a cover releasably mounted on the upper end of the base 10 and above the cover, the stub portion terminates in a smaller, smooth portion which is provided with a small pinion 27 that is driven thereby. This pinion meshes with a ring gear 29 that is fixed to the outer surface of a sleeve hopper 30 which is turnably disposed in an opening 31 in cover 25. For retaining the sleeve in position and also for covering the gear and pinion, a cover 35 is provided that is secured by screws to the upper side of the cover 25. It will be noted that the covers 25 and 35 by substantially contacting the ring gear, hold the sleeve in vertical position.

The lower end of the sleeve 30 is disposed above the disc 20 so that a potato 37 in the sleeve will rest on the upper surface of the disc. For the purpose of cutting slices or chips from the potato, the disc, as best shown by Figures 3 and 4, has a cutter blade 39 secured thereto and this blade has a blade portion 39 projecting upwardly through an opening 40 in the disc. The blade is secured to the disc by means of a flat portion 42 disposed at the under side of the disc which is secured to the latter by means of screws 43 that have substantially flat heads at their upper sides so as to eliminate interference of the disc movement along the under side of the potato. The cutting portion of the blade is corrugated, as will be best seen in Figs. 1 and 3, and the bottoms of the corrugations terminate substantially along a line indicated at 50 in Fig. 4, so that the bottoms of such corrugations are disposed in spaced relation to the top side of the disc 20. The cutter blade is tapered upwardly through the opening 40 in the disc and at its front side is so arranged that slices cut from the potato move downwardly between the under side of the blade and the advancing side of the opening 40. For receiving the chips so sliced from the potato, an inclined plate 47 is disposed within the base and this plate leads to a discharge opening 48, whereby the slices are discharged to the outside.

The parts are so constructed and arranged that during each revolution of the disc 20, the sleeve 30 turns one quarter of a revolution and from this it will be seen that the corrugations cut in the bottom side of the potato during one cutting movement of the blade are disposed approximately at right angles to the corrugations that will be formed in the lower side of the potato during the succeeding action of the cutter. It follows from this that the corrugations formed on one side of the slice removed from the potato

will be disposed substantially at right angles to the corrugations formed at the other side of the slice. While it would be possible to hold the potato stationary during the short interval the cutter is passing through the potato, the device works satisfactorily even though the potato is turning very slowly, during which curving of the corrugations occurs.

The depth of the corrugations and the location of the bottoms thereof at the line indicated at 50, in spaced relation to the upper side of the disc, insures that the slices or chips will be unitary and not separated. While the depth of the slice may be varied by raising the line 50 defining the bottoms of the corrugations in the cutter, it is desired that the thickness of the chips be such that corrugations formed in the upper side of the chip will intersect the corrugations formed in the bottom side of the chip so as to form small openings at the points of intersection. By this is meant, that the bottoms of the corrugations in the upper side of the chip and the bottoms of the corrugations in the lower side of the chip will intersect and thus form openings at the points of intersection. The size of these openings may be varied by varying the thickness of the chip, so as to bring the upper and lower corrugated surfaces closer or farther apart. If the corrugations are too far apart, or, in other words, if the thickness of the chips is too great, the bottoms of the corrugations on opposite sides of the chip will not intersect to form openings, while if the thickness of the chips is insufficient, the chip would be formed in separated sectors.

In order to insure rotation of the potato with the sleeve and at the same time provide a means for applying downward pressure on the potato, as may be desired, a plunger 51 is vertically slideable in the sleeve and this plunger includes a lower section 52, such as constructed of wood, an intermediate rubber section 53 having frictional contact with the sides of the sleeve, and an upper rigid section 54. Bolts 55 connect the sections. For moving the plunger upwardly or downwardly, a reciprocatory rod 56 is provided which is fastened to the inner race 57 of a ball bearing, the outer race 58 of which is fixed to the plunger section 54. It is to be understood that the parts are constructed and arranged to effect movement of the plunger upwardly and downwardly by movement of the rod while allowing the sleeve to turn relative to the rod.

Rod 56 is slideable in bearings 60 and 61 retained on cross members 62 and 63 of a bracket having legs 64, 65, and 66 secured to the cover 25. A handle 70 is connected to rod 56 for moving it and this handle has a lateral portion 71 which limits downward movement of the plunger by engagement of the hand portion with the bearing 60, so that the plunger will not engage the cutter blade. A spring 73 normally urges the rod downwardly so that the potato is resiliently urged against the disc.

It is understood that with the potato resting on the disc 20, the first rotation of the cutter severs a chip from the potato and that as soon as the cutter passes through the potato, the latter moves downwardly so as to again rest on

the disc surface and be in a position for a succeeding action of the cutter. As the cutter continues its turning movement, the potato is turned, and when the cutter again passes through the potato, the corrugations in the cutter blade are at right angles to the corrugations that were formed in the potato during the preceding cutting action.

In Fig. 5, a chip is generally indicated at 14 on an enlarged scale. The corrugations at the upper side of the chip are indicated at 75, the corrugations at the lower side at 76, and the openings at the intersections are indicated at 77.

Although only one form of the invention has been described and illustrated in detail, it will be apparent to those skilled in the art that various modifications may be made without departing from the scope of the appended claims.

What is claimed is:

1. A mechanism for cutting potato chips or the like, comprising a hopper for receiving a potato, means for advancing the potato through the hopper to a discharge point, a rotary disc disposed adjacent the discharge end of the hopper and having a corrugated cutter blade at one point, the parts being arranged so that the potato rests on the disc and is advanced to the disc each time a chip is cut from the potato by the blade, means for turning the hopper about an axis parallel to the rotary axis of the disc, means for holding the potato in the hopper so that it rotates therewith, and means for rotating the hopper and disc in such synchronized relation that the corrugations formed on one side of each slice removed from the potato extend transversely to the corrugations on the opposite side of the slice.

2. A mechanism for cutting potato chips or the like comprising a base, a driving shaft extending upwardly from the base, a rotary disc mounted on the shaft for rotation therewith and having an opening at one point, a corrugated cutter blade mounted on the upper side of the disc adjacent the opening and being adapted to cut sections from a potato as the latter is pressed against said upper side of the disc and the latter is rotated, a side housing wall on the base and extending around the disc and projecting above and below the margin of the disc, a hopper rotatable about a vertical axis and supported by the wall at the upper side of the disc for feeding a potato downwardly to the disc, said housing wall below the disc having an opening beneath the location of the hopper in order to discharge chips, an inclined bottom wall under the disc and extending across the housing, with the wall inclining upwardly from the lower edge of the discharge opening to a point adjacent the diametrically opposite edge of the disc and having a central opening through which the shaft extends downwardly, means connected to the lower end of the shaft for driving the latter, and means drivingly connecting the upper end of the shaft to the hopper for rotating the latter simultaneously with the rotation of the disc but at a different speed.

DONALD A. BARNES.
